UNITED STATES PATENT OFFICE

2,346,871

AIRPLANE SAFETY CHAIR

Gaetano Provenzano, Greenwich, Conn.

Application May 28, 1941, Serial No. 395,580

3 Claims. (Cl. 155—189)

This invention relates to devices for confining an occupant in a seat, and more particularly to such seats as are used in airplanes.

It is well known that such travellers are ordinarily confined to their seats, by straps adjusted by operatives of the airplane, and released only at their discretion.

An object of this invention is to provide a pair of opposed gates, pivoted to the seat frame in a manner to fold over the lap of the seat occupant coincidently with becoming seated therein.

A further feature is in the provision of automatic restraining means adapted to retain a person on the seat, but permitting rising upon removal of their weight from the seat.

Another purpose is to produce means for locking the restraining gates by the occupant.

These objects, and others analogous thereto, are accomplished by the novel construction, combination and arrangement of parts hereinafter described and shown in the annexed drawings, forming part hereof, and in which—

Figure 1 is a side elevational view of an embodiment of the invention showing the seat as unoccupied, certain parts being in section.

Figure 2 is a front view of the same.

Figure 3 is a partial perspective view of the operative parts of the device in closed position.

Figure 4 is a fragmentary view of the gate actuating bar.

Figure 5 is a partial side view of the parts shown in Figure 3.

Referring to the drawings, numeral 15 designates in general the wall of the cabin or fuselage of a conventional type of airplane, having a floor 16 and provided with a window 17.

Fixed on the floor is a circular base 18, in which is set an upright rigid post 19 having a fixed collar 20.

A helical expansion spring 21 is loosely coiled around the post, its lower end being seated on the collar 20, while its upper end is encased in a sleeve 22, closed at its top in a manner to be supported by the spring, around which the sleeve is freely rotatable.

A circular flange 23, formed on the upper end of the sleeve, is attached to the under side of a chair frame 25 having a rearwardly inclined back rest 26, connected to the main frame by arm rests 27, having forwardly inclined, down-reaching supports 28, which at their junction with the main frame 25, are provided with forwardly extending lugs 29.

A horizontal shaft 30 is rotatably mounted in

these lugs, being confined therein by washers 31 held by nuts 32.

Forwardly bowed arms 34 rise from the lugs 29, and are connected with the supports 28 by arcuate members 35, concentric with the axis of the shaft 30.

Adjustably fixed, on the outer sides of the members 35, are bearings 36, held in adjustment by bolts 37, threaded into the member 35, whereby the bearings may be moved towards and from the chair back 26.

These bearings are receptive of round bars 38 pivotally mounted on stems 39 extending radially from the peripheries of discs 40, which are keyed to the end portions of the shaft 30.

Fixed on upper extending ends of the bars 38 are flag-like gates 41, capable of being swung outwardly as shown in Fig. 1, or of closing over the front of the chair.

Motion is communicated to the bars 38 by reason of pinions 44, fixed on their lower portions, these pinions engaging with curved racks 45 actuated in the following manner.

A seat having its frame 46, pivoted on the shaft 30, is provided with a cushion and is normally held in an upwardly inclined position by springs 47 resting on the main frame 25.

The forward elements of the side members of the seat frame 46 terminate in essentially circular plates 48, having lugs 49 adapted to limit the rise of the seat by reason of contact with the forward ends of the main frame 25.

The plates 48 also carry the racks 45, whereby motion of the seat 46 is transmitted to the gates in accordance with its position.

If at times it is desirable to prevent the chair from rotating on the axis of the post 19, a plate 50 is secured to the wall 15, the plate having a vertical slot 51 receptive of a stud 52 fixed in a vertical bar 53 rigidly carried by the chair frame.

In operation, the weight of a person when seated in the chair causes the seat to move downwardly, turning the gates into closed position, confining the occupant until released by rising.

It will be apparent that the gates may be had when closed, avoiding danger due to shocks or the position the airplane may assume.

What is claimed as new and sought to secure by Letters Patent is:

1. In combination, a chair having a frame and a seat hinged at its front edge to the frame, springs interposed between said frame and seat normally inclining said seat upwardly near the

rear, normally upright bars rotatably mounted at the front of said frame on both sides thereof, rack and pinion means to rotate said bars upon the application of weight to said seat whereby it is caused to assume a level position, and confining means carried by said bars to fold above and across said seat when influenced by weight on said seat.

2. In combination, a chair having a frame and a seat hinged at its front edge to the frame, springs interposed between said frame and seat normally raising said seat at the rear, normally erect bars rotatably mounted at the front of said frame on both sides thereof, racks carried by said seat, pinions on said bars engaged with said racks whereby to rotate said bars when said seat is oc-

cupied and assumes a substantially level position, and restraining means affixed to said bars adapted to confine an occupant on said seat when sitting thereon.

5. In combination, a chair having a frame and a seat hinged at its front edge to the frame, said seat being normally inclined upwardly near the rear, springs to cause inclination of said seat, interposed between said frame and seat, normally upright bars mounted rotatably at the front corners of said frame, means actuated by a person sitting on said seat to rotate the bars, means to confine a person on said seat carried by said bars, and means to retain said confining means when in operative position.

GAETANO PROVENZANO.
